UNITED STATES PATENT OFFICE.

JOHN B. GLOWACKI, OF CHICAGO, ILLINOIS.

RENEWABLE FUSE ELEMENT.

Application filed March 9, 1922. Serial No. 542,253.

To all whom it may concern:

Be it known that I, JOHN B. GLOWACKI, a citizen of the Republic of Poland (having declared my intention of becoming a citizen 5 of the United States), and a resident of the city of Chicago, in the county of Cook and State of Illinois, have invented certain new and useful Improvements in Renewable Fuse Elements; and I do hereby declare that 10 the following is a full, clear, and exact description of the same, reference being had to the accompanying drawings, and to the numerals of reference marked thereon, which form a part of this specification.

15 It is an object of this invention to provide a fusible element for use in electrical fuses which shall be adapted for each of several different types of fuse cartridge.

It is a further object of this invention to 20 provide a fusible element which shall be quick and certain in its action.

It is a further object of this invention to provide a fusible element with a scored place near each of its ends whereby the ends 25 may be broken off so that the central part of the element may be used alone.

It is a further object of this invention to compensate for such scored places so that the conductivity of the fuse shall not be 30 altered thereby.

Other and further important objects of this invention will be apparent from the disclosures in the accompanying drawings and specification.

35 The invention (in a preferred form) is illustrated on the drawings and hereinafter more fully described.

On the drawings:

Figure 1 is a sectional view of a cartridge 40 containing the fusible element.

Figure 2 is a top plan of the fusible element.

Figure 3 is a side view thereof.

Figure 4 is an end view.

45 Figure 5 is a section upon an enlarged scale of a portion of the fusible element near one end.

As shown on the drawings:

The cartridge 1 has the usual cylindrical 50 container of fiber or other insulating material provided with caps 2 which screw on at each end and compress the ends 4 and 5 of the fusible element 6 between the washers 7 and the closure plates 8 to which the contact blades 9 of the cartridge are secured.

The end 4 of the fusible element 6 stands at right angles to the main body of the fusible element. For convenience in assembling, the end 5 makes a small angle with the main body of the fusible element, as 60 shown at 10.

The fusible element, as most clearly shown in Figure 2, is narrowed at a plurality of places 11 to make parallel sections at which the current density shall be greatest so that the element will be likely to melt first at these places. Instead of producing this narrowing by angular cuts in the edge of the strip, the corners have been rounded 70 as indicated at 12. A series of broad portions of the strip separated by the narrow portions 11 extends from one end of the fusible element to the other. But at each end of the strip, a broad portion 14 is provided, and these are wider than the broad portions just mentioned. In line with the narrow portions 11 and in the middle of each of the broad portions 14 is provided a hole 15. Beyond this hole toward the end of the strip is a scored or indented or grooved place 16. This is best shown in Figure 5 but for the sake of making the illustration clear, the depth of the groove is greatly exaggerated in this figure. Holes 75 17 and 18 are provided in the end portions of the strip beyond the bent parts thereof to allow of the escape of gases through the vent passages formed in the ends of the fuse cartridge.

In the use of this device with the cartridge of the form shown in Figure 1, the bent portions 4 and 5 being clasped between the metallic parts that form the end of the cartridge serve to support the strip and at the same time to afford good electrical connection between the strip and the contact blades 9. If the strip is used with a form of cartridge in which the end arrangements use posts or screws, the holes 15 will accommodate such posts or screws. In many forms of fuse cartridge there are posts which are at right angles to the length of the strip. In the use of this fuse with such a cartridge, the bent ends of the fuse must be removed in order that they shall not be in the way. The grooves 16 by weakening the fuse provide a definite point at which the bent ends may be broken off, leaving a fuse of suitable length for the type of cartridge last mentioned.

When current flows through the fuse, the grooves 16 tend to produce an increased resistance, but to counteract this, the portions 14 of the strip are made wider than the rest 5 of the strip so that there will be no excessive heating at the grooved places. When the current through the fuse increases, the fuse will break down first at one of the points 11. It may happen that an arc will form between the two wider portions of the fuse at 10 various points at the moment that the narrow part 11 melts. If this should occur, the curved character of the edges of the wider parts acting on the principle of the horn-type lightning arrester will quickly stop such arc by causing it to travel to the outer edge of the strip where the gap is longer than the arc can span. Because there are no sharp corners at this outer edge, no local discharge 15 can occur there to maintain the arc.

I am aware that numerous details of construction may be varied through a wide range without departing from the principles of this invention, and I therefore do not pur-

pose limiting the patent granted, otherwise 25 than necessitated by the prior art.

I claim as my invention:

1. A strip of fusible conducting material having end portions each at an angle to the plane of the main body of the strip, and 30 weakened portions separating said end portions from the main body of the strip.

2. A strip of fusible material having four holes therein, a pair near each end, said strip having a weakened portion between the 35 holes of each pair.

3. A strip of fusible material adapted for use in each of several types of cartridge, and having weakened portions whereby the strip may be broken so that a portion thereof may 40 be used to fit a different type of cartridge.

In testimony whereof I have hereunto subscribed my name in the presence of two subscribing witnesses.

JOHN B. GLOWACKI.
